E. W. FENN,

PASS TYPE ELEVATOR DOOR.
APPLICATION FILED SEPT. 13, 1921.

Patented Aug. 1, 1922.

Emery W. Fenn Inventor

By his attorney
Frank T. Wentworth

UNITED STATES PATENT OFFICE.

EMORY W. FENN, OF CHICAGO, ILLINOIS, ASSIGNOR TO THE PEELE COMPANY, OF BROOKLYN, NEW YORK, A CORPORATION OF NEW YORK.

PASS-TYPE ELEVATOR DOOR.

1,424,288.

Specification of Letters Patent. Patented Aug. 1, 1922.

Application filed September 13, 1921. Serial No. 500,286.

To all whom it may concern:

Be it known that I, EMORY W. FENN, a citizen of the United States, residing at Chicago, in the county of Cook and State 5 of Illinois, have invented certain new and useful Improvements in Pass-Type Elevator Doors, of which the following is a specification, reference being had therein to the accompanying drawings, which form a 10 part thereof.

My invention relates to pass type elevator doors, and more particularly to the arrangement of the suspension means connecting two oppositely movable, vertically sliding 15 door sections, so as to permit the maximum range of movement of the upper door section.

In pass type elevator doors of the type to which my invention relates, the door sections are mounted in an elevator shaft by 20 means of a guide rail structure which will bring the door sections close to the wall of a shaft about the door opening when they are in the closed position, while positioning them away from the wall as they are being 25 opened so as to permit the upper door section to recede from the wall of the shaft and pass a closed door at the opening immediately above it and the lower section to similarly pass a closed door at the opening 30 immediately below it.

With this type of door the height of the door opening may be very much greater than with the ordinary type of vertically movable, two-section doors, since space between the sill of one door opening and the 35 lintel of the door opening below need not be considered in providing for the door structure.

Where the space between door openings 40 in different floors is small, I have found it necessary in providing for the maximum range of movement for the upper door section particularly, to use a particular arrangement of sheaves and of the flexible 45 connections between the door sections, to compensate for the horizontal component of movement of the upper door section and avoid interference between the two reaches of said flexible connections, which particular arrangement is made the subject matter 50 of my present application.

The detailed construction of the guide rails and of the door structure co-operating

therewith is immaterial to the present invention, such being made the subject matter 55 of a separate application for patent.

The invention consists primarily in a pass type elevator door embodying therein in combination with a door consisting of a plurality of oppositely, vertically movable 60 sections, and a guide rail structure therefor consisting of a short guide section adjacent the meeting point of the door sections, guide sections parallel therewith, spaced within the shaft towards the lintel, and the sill, of 65 a door opening respectively, and oblique guide sections connecting said short and said other guide sections, of sheaves adjacent the lintel of the door opening upon opposite sides thereof, the axes of which are 70 parallel with the wall of a shaft adjacent said opening, and a flexible connection between said sections passing over said sheave, the reach of said connection attached to a downwardly movable section passing between 75 said sheave and the wall of the shaft, and the reach of said connection attached to an upwardly movable section passing about said sheave from within the shaft toward the wall thereof; and in such other novel 80 features of construction and combination of parts as are hereinafter set forth and described, and more particularly pointed out in the claims hereto appended.

Referring to the drawings,

Fig. 1 is a condensed view of a pass type elevator door embodying my invention, from within a shaft;

Fig. 2 is a side view thereof; and

Figs. 3 and 4 are diagrammatic views 90 showing the position of the suspension means with the door in the closed position, and with the door in the open position, respectively.

Like letters refer to like parts throughout 95 the several views.

In the embodiment of my invention shown in the drawings, I have indicated at *a* and *b* the upper and lower sections of an elevator door, said sections being vertically movable in opposite directions in opening and closing the door, this movement having a horizontal component so that as a door is opened, both sections will automatically move away from the wall of an elevator 105 shaft adjacent the door opening for a dis-

tance sufficient to permit said sections to pass closed doors at a door opening above and below the door that is being operated.

This movement is under the control of 5 means carried by the door co-operating with guide rail structures on the wall of the shaft at each side of the door opening, which include short guide sections *c* adjacent the meeting point of the doors, guide sections 10 *d* parallel therewith and adjacent the lintel of the door opening, and guide sections *e* also parallel with the sections *c*, adjacent the sill of the door opening, said sections *d* and *e* being spaced within, or away from 15 the wall of, the shaft adjacent said opening for a distance greater than the sections *c*.

The sections *c* and *d* of each guide rail structure are connected by an oblique by an oblique section *f* while the sections *c* and *e* 20 are connected by a similar oblique section *g*.

The various guide rail sections above referred to are carried upon each side of the door by what is known as a wall angle *h*, which is cut away at *h'* in conformity with 25 the adjacent rail sections so as to provide clearance for the hanger bar *b'* of the lower door section *b*.

The upper door section is provided with 30 a hanger bar *a'*, the length of which is somewhat shorter than that of the section *b'* so as to offset the two reaches of the flexible connection between these door sections with relation to each other, thus avoiding interference of said reaches when the 35 door sections are in motion or when the door is closed.

Secured to the wall rail *h* adjacent the lintel of a door opening, is a fitting *i* carrying a sheave *j* about which the flexible connection 40 between the door sections *a*—*b* passes, one reach *k* of said connection being secured to the hanger bar *a'* while the other reach *m* thereof is connected by means of the rod and turn buckle *n* with the hanger bar *b'*. 45 The axis of the sheave *j* extends parallel with the wall *o* of the elevator shaft.

To permit the door section *a* to be raised to the maximum extent, the reach *k* is passed about the sheave *j* in a direction from within 50 the shaft toward the wall *o*, the reach *m* of said connection passing between said sheaves and the wall *o*.

The parts *i*, *j*, *k*, *m* and *n* are duplicated upon opposite sides of the door.

55 By the construction described, when the door is in the closed position, the two reaches *k* and *m*—*n* converge toward each other being upon substantially the same vertical plane laterally of the door as shown in 60 Fig. 2, but so spaced as to be offset in relation to each other, as shown in Fig. 1.

As a door is opened, both reaches of the chain at their point of connection with their respective door sections will have a 65 movement inwardly of the shaft, the hanger

bar *a'* of the section *a* when it reaches the fully open position, being adjacent the sheave *j*. During the entire movement of the door either in opening or closing, the point of connection of the turn buckle *n* and the reach *k* of the chain will occupy corresponding vertical planes as to each other, and a vertical plane parallel to that which they occupy when the door is fully closed. The lateral deflection of these chains due 70 to the length of the respective hanger bars *a'* and *b'*, and the positions of the sheaves *j* upon opposite sides of the door, is never sufficiently great to cause the flexible connection to ride upon the rim 75 of the sheave. The mounting of this sheave upon the wall rail *h* and the diameter of said sheave is such that when the door is in the fully opened position, the point of connection of the reach *k* will be 80 closely adjacent the perimeter of said sheave but positioned a short distance between same and the door section *a*. In fact by employing this construction, merely enough room between floors is required to mount the 85 fitting *i*, ordinary floor beams affording sufficient clearance to permit the functioning of the door.

It will be noted that at no time do the two reaches *k* and *m*—*n* of the flexible connection between the door sections *a* and *b* cross the same vertical plane, thus permitting the hanger bar *a'* to be brought into the close proximity to the sheave *j* above referred to.

100 While a pass type door of the type to which my invention relates can be operated with the reach *m* attached to the hanger bar *a'*, and the reach *k* attached to the turn buckle *n*, such a construction necessitates the 105 mounting of the fitting *i* a greater distance above the lintel of the door opening, or the provision of greater clearance between floors for the operation of the door, to avoid like-lihood of interference of the two reaches if 110 when opening the door the hanger bar *a'* be brought close to the sheave. At the same time this construction will cause one reach of the flexible connection to cross the plane of movement of the other reach, which is not 115 a desirable practice.

The hanger bar *a'* is carried by the section *a* toward the bottom thereof, while the hanger bar *b'* is carried by the section *b* adjacent the top thereof, a practice common to 120 vertically movable elevator doors, the sections of which have movement in opposite directions.

The invention herein described resides solely in the arrangement of the sheaves and the flexible suspension means with relation thereto, other characteristics shown in the drawings being capable of wide variation without departing from the spirit and scope 125 of the invention.

Having described the invention, what I claim as new and desire to have protected by Letters Patent, is:—

1. A pass type elevator door embodying therein in combination with a door consisting of a plurality of oppositely, vertically movable sections, and a guide rail structure therefor consisting of a short guide section adjacent the meeting point of the door sections, guide sections parallel therewith, spaced within the shaft towards the lintel, and the sill, of a door opening respectively, and oblique guide sections connecting said short and said other guide sections, a wall angle carrying said guide sections respectively, said wall angle being cut away in conformity with said guide rail sections, of sheaves carried by said wall angles adjacent the lintel of the door opening upon opposite sides thereof, the axes of said sheaves being parallel with the wall of a shaft adjacent said opening, and flexible connections between said sections passing over said sheaves respectively, the reach of each connection attached to a downwardly movable section passing between the respective sheave and the wall of the shaft, and the reach of said connection attached to an upwardly movable section passing about said sheave from within the shaft toward the wall thereof.

2. A pass type elevator door embodying therein in combination with a door consisting of an upper section, a laterally projecting hanger bar adjacent the bottom thereof, a lower section, a hanger bar adjacent the top thereof of relatively greater length than the hanger bar of said upper section, said sections being vertically and oppositely movable with relation to each other, a guide rail structure therefor consisting of a short guide section adjacent the

meeting point of the door sections, guide sections parallel therewith and spaced within the shaft towards the lintel, and the sill, of a door opening respectively, and oblique guide sections connecting said short and said other guide sections, a wall angle carrying said guide sections respectively, said wall angle being cut away in conformity with said guide rail sections, of sheaves carried by said wall angles adjacent the lintel of the door opening upon opposite sides thereof, the axes of said sheaves being parallel with the wall of a shaft adjacent said opening, and flexible connections between said sections passing over said sheaves respectively, one reach of said each connection being connected to the hanger bar of said lower door section and passing between the respective sheave and the wall of the shaft, and the other reach of said connection being attached to the hanger bar of said upper door section and passing therefrom about said sheave toward the wall of the shaft, whereby the ends of said reaches will be offset laterally with relation to each other, and no part of said flexible connection, with the opening or closing of the door, will pass the plane of movement of another part of said connection.

In witness whereof I have hereunto affixed my signature, in the presence of two subscribing witnesses, this 30th day of August 1921.

EMORY W. FENN.
